(57) **CLAIM**

The ornamental design for an outlet of air conditioning for aircraft, as shown and described.

DESCRIPTION

FIG. 1 is a perspective view of an outlet of air conditioning for aircraft according to my new ornamental design.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof.

FIG. 8 is an enlarged cross-sectional view taken along the line 8-8 in FIG. 2.

FIG. 9 is an enlarged cross-sectional view taken along the line 9-9 in FIG. 2; and,

FIG. 10 is a referential view showing use thereof.

The outlet of air conditioning for aircraft is shown with a symbolic break in its length on one end. The appearance of any portion of the article outside the break lines forms no part of the claimed design.
